INSULIN KIT

Lloyd G. Green, Denver, Colo.

Application May 8, 1944, Serial No. 534,641

2 Claims. (Cl. 206—63.2)

1

This invention relates to an insulin kit and has for its principal object the provision of a simple, neat and compact kit which can be conveniently carried in the pocket or hand bag of an insulin user and which will maintain the syringe and needle in an antiseptic solution when not in use; which will provide protection for the insulin bottle and needle in the same container with the syringe and solution; which will provide a convenient and sanitary supporting rest for the syringe when it is removed from the container; which will provide convenient means for sharpening the needle; and which will support the entire assembly of bottle, syringe and needle as a unit so as to allow removal of all elements from the container simultaneously.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a vertical section through the improved insulin kit with the bottle and syringe in place therein;

Figs. 2, 3, 4 and 5 are cross sectional views taken on the section lines of their respective numbers in Fig. 1;

Fig. 6 is a top view of the improved kit; and

Fig. 7 is a detail view illustrating a supporting clip employed in the kit.

In the drawing the various elements of an insulin kit are designated by numeral as follows: insulin bottle 18, syringe 19, syringe plunger 20, hypodermic needle 21, and plunger holder 22.

The improved kit employs a cylindrical receptacle 10 of glass or other suitable solution-proof material partially filled with alcohol 28 or other suitable antiseptic fluid. The receptacle 10 has a closed bottom 11 and a threaded neck 12. An internal shoulder 13 is formed within the neck 12 below the open extremity thereof to support an annular resilient gasket 14 of exceedingly soft flexible material such as soft rubber. The receptacle 10 is closed by means of a cylindrical cap 15 having internal threads to be threaded onto the neck 12 of the receptacle 10.

The cap 15 is closed at its top and the closed top thereof contains a groove 16, to serve as a rest for the hypodermic syringe 19, and an im-

2

bedded whetstone 17 to be used for sharpening the hypodermic needle 21. The cap 15 is designed for containing the insulin bottle 18 and the receptacle 10 is designed for containing the hypodermic syringe 19, its plunger 20 and its needle 21.

The syringe 19 is suspended on its plunger by means of the friction plunger holder 22 with which standard insulin syringes are provided. The plunger 20 is suspended from the neck of the insulin bottle 18 by means of a spring wire clip 23, which is illustrated in detail in Fig. 7.

The clip 23 is formed with an upper loop 24, which is shaped to be snapped around the neck of the insulin bottle 18, and with separated, looped extremities 25, which are snapped around the plunger 20 below the head thereof.

The needle 21 is protected by means of a sleeve 26 of rubber or similar flexible material which is slipped over the shank of the needle 21. The lower portion of the sleeve 26 may be filled with porous pervious material, such as sponge rubber 27, into which the needle is inserted for further protection. A cushion 29 of absorbent cotton, sponge rubber or other material is placed in the bottom of the receptacle for further protection of the needle.

The user removes the cap 15 and sets it to one side of the receptacle 10. He then grasps the insulin bottle 18 drawing it upwardly. The resilience of the gasket 14 allows the clip 23 and the syringe with its attached needle and tube 26 to be withdrawn through the gasket. If desired, the gasket 14 can be made to withdraw and remain about the neck of the bottle 18. It is preferred, however, to have the gasket remain in the receptacle and to withdraw the elements through the open center thereof. The user then slips the plunger 20 from the looped extremities 25 of the clip 23 and removes the tube 26 from the needle and the elements are ready for use. The groove 16 provides a convenient sanitary rest for the syringe during the preparatory steps.

When the injection is completed the tube 26 is slipped over the needle, the plunger 20 is slipped into the clip 23 and the entire assembly is slid through the opening in the gasket 14 until the bottle 18 rests against the gasket. The cap 15 is then screwed into place against the bottle 18 so as to force the latter tight against the gasket 14 to seal the receptacle and prevent escape of the alcohol 28 or other antiseptic fluids.

The sponge rubber 27 when removed from the needle can be used as a sterilizing pad for sterilizing the skin before the injection. It always re-

mains sterile since it is constantly immersed in the antiseptic 28.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. An insulin kit comprising: a tubular container closed at one extremity; a threaded neck on the other extremity of said container; an annular resilient gasket within the open extremity of said container; an inverted bottle resting on said gasket, said bottle having a narrowed neck projecting downwardly through said gasket into said container; a cap threaded onto the threaded neck of said container, said cap enclosing and contacting the upturned bottom of said bottle and forcing the neck through and into sealing contact with said gasket; a hypodermic syringe; and means on the neck of said bottle for supporting said hypodermic syringe within said container.

2. An insulin kit comprising: a tubular container closed at one extremity; a threaded neck on the other extremity of said container; an annular resilient gasket within the open extremity of said container; an inverted bottle resting on 30 said gasket, said bottle having a narrowed neck

projecting downwardly through said gasket into said container; a cap threaded onto the threaded neck of said container, said cap enclosing and contacting the upturned bottom of said bottle and forcing the neck through and into sealing contact with said gasket; a hypodermic syringe; a plunger projecting upward from said syringe; means on the neck of said bottle for supporting said hypodermic syringe within said container, said latter means comprising a length of spring wire, a loop formed at the middle portion of said wire for receiving the neck of the bottle and looped extremities on said wire engaging the plunger of the hypodermic syringe.
